UNITED STATES PATENT OFFICE.

FREDERICK F. BIOREN AND JAMES C. BIOREN, OF NEWARK, NEW JERSEY.

DESIGN FOR A SLEEVE-BUTTON.

SPECIFICATION forming part of Design No. 14,897, dated March 25, 1884.

Application filed November 3, 1883. Term of patent 14 years.

To all whom it may concern:

Be it known that we, FREDERICK F. BIOREN and JAMES C. BIOREN, citizens of the United States, residing at Newark, in the county of Essex and State of New Jersey, have invented a certain new and original Design for Sleeve-Buttons and other Jewelry; and we do hereby declare the following to be a full, clear, and exact description of the design, such as will enable others skilled in the art to which it appertains to make and use the same, reference being had to the accompanying drawings, and to letters of reference marked thereon, which form a part of this specification.

15 Figure 1 represents a sleeve-button or other piece of jewelry embodying our design. Fig. 2 is an enlarged plan of a portion of the same, and Fig. 3 an edge view, said figures being deemed sufficient to illustrate the nature of the 20 design, which consists in the sleeve-button or other piece of jewelry having the shape described.

The drawings represent a piece of jewelry

with letter-shaped protuberances, which are outlined by regular surfaces *b b*, lying at an 25 angle to the surface *c*, as shown. The letter-shaped projecting portions may have the configuration of any of the letters of the alphabet. Between the surfaces *b b* the raised surfaces are foliated and flowered in configuration, or 30 are shaped in imitation of a mixture of flowers and leaves. The leaves and flowers may be formed in imitation of natural ones, or they may be conventionalized.

What we claim is—

35 In a sleeve-button or other similar article of jewelry, the design which consists in the initial-letter, as shown and described.

In testimony that we claim the foregoing we have hereunto set our hands this 26th day of 40 October, 1883.

F. F. BIOREN.
